UNITED STATES PATENT OFFICE.

KARL JOHAN SVENSSON, OF LIDINGO VILLASTAD, AND KARL AXEL PATRIK NORLING,
OF SODERTORNS VILLASTAD, SWEDEN.

DRUM FOR CENTRIFUGAL SEPARATING APPARATUS.

Application filed December 11, 1926, Serial No. 154,111, and in Sweden December 29, 1925.

When centrifugally separating liquid mixtures, comprising two or more liquids of different specific gravities, and containing solid particles of various kinds in suspension, 5 the separated solids of a specific gravity higher than that of the heaviest fluid ingredient remain in the drum. If the percentage of these solids be relatively large the drum will be filled by slime or the like 10 in a very short time and, consequently, must be stopped frequently for cleaning, especially so in the case of the well known type of centrifugal drum fitted with plates, as the so called slime chamber, i. e. the free space between the plates and the outer walls of the 15 drum is small relatively to the capacity and separating efficiency of the drum. By arranging the outlet for the separated heavier fluid ingredients in such a way that their 20 velocity is maintained high during their passage from the outer parts of the drum (the slime chamber) to the actual discharge from the drum (nearer to the centre) a large proportion of the slime with a specific gravity 25 only slightly exceeding that of the heavier liquid can be conveyed by, and discharged together with, that liquid, thus enabling the drum to be run a considerably longer time without stop than if all the solids were to 30 remain therein.

This capability of the drum to discharge continuously a large proportion of the separated slime is obtained by conducting the separated heavier liquid or liquids from the 35 slime chamber through a number of narrow tubes, or better still through narrow channels or grooves situated on the upper side of the so called top plate, i. e. that part which keeps apart the separated fluid components during 40 the discharge from the drum. The position of the entrances within the drum (in the slime chamber) to said tubes or channels is, however, of great importance. If the liquid mixture contains only solids of such specific 45 gravity that they can be conveyed by the fast flowing heavier fluid ingredients, these entrances should be situated in the outer part of the slime chamber so that the smallest possible amount of solids will accumulate 50 inside the drum. But if this arrangement be used for separation of a mixture containing a large proportion of heavy solid particles, such as metal chips, sand, grit or the like, which solids cannot be washed out together 55 with the heavier liquid, these particles would

soon fill and choke up the small space outside the entrances to the channels, after which no separation of the liquids would take place until the drum is cleaned; consequently the drum should be stopped long 60 before the slime chamber is filled by solids. For a liquid mixture of the latter kind the entrances to the channels should be situated at a greater distance from the outside walls of the drum, this distance varying in relation 65 to the proportions and characters of the different solids present in the mixture.

The present invention has for its object an improved arrangement to enable a centrifugal drum for the above mentioned purpose 70 to run as long as possible without being choked, when separating solid particles and impurities of different kinds from a liquid mixture.

According to this invention a centrifugal 75 drum for the continuous separation of fluid mixtures, as mentioned above is provided with means for varying the distance from the centre of the drum to the entrances of the channels, which entrances lead from the so-called slime chamber, so that the largest 80 possible quantity of solids can be separated without said entrances becoming choked, thus enabling the separation to continue as long as possible without any stop for cleaning 85 purposes. Four different arrangements of the invention are illustrated by the accompanying drawings in which Figures 1, 3, 5, 7, 9, 11, 13 and 15 show in sectional elevation centrifugal drums arranged according 90 to this invention and Figures 2, 4, 6, 8, 10, 12, 14 and 16 show part horizontal sections on the lines 2—2, 4—4, 6—6, 8—8, 10—10, 12—12, 14—14 and 16—16, Figures 1, 3, 5, 7, 9, 11, 13 and 15 respectively, with the top part of 95 the drum removed. In all the Figures *a* is the bottom part of the drum, *b* the top part or bonnet thereof, *c* a ring nut for holding together the bottom and top parts *a* and *b*, *d* is a receiver and distributor for liquid fed into 100 the device, *e* is an interior arrangement consisting either of a number of conical plates of known design or of radial wings extending outwards from the distributor *d*, *f* is the so-called top plate, which keeps apart 105 the separated heavy and light liquids during their discharge from the drum *a*. The top plate *f* is formed on the upper side of its conical part with radial grooves or channels 110 *g*, (or said grooves or channels may be

formed in the underside of the bonnet *b*) leading to the outlet *h* for the heavy liquid, and said top plate *f* is provided with a neck *j* open at the top, and constituting the outlet *k* for the light liquid.

In Figures 1 and 2 is shown a top plate *f* with the entrances *m* of the channels *g* near to the outer wall of the drum *a*, an arrangement suitable for separation of fluid mixtures containing relatively light solids only. By replacing this top plate by one *f'* as shown in Figures 3 and 4, the drum can be adjusted in a simple way for separating liquids containing both relatively heavy and light solids as in the last mentioned top plate the entrances *m'* to the channels *g* are situated at a considerably greater distance from the walls of the drum *a*, thus, the slime chamber can be filled to a greater extent by heavy solids without the channel entrances becoming choked.

Figures 5, 6, 7 and 8 show an arrangement where the channels *g* are formed in the top part *b*. In Figures 5 and 6 the outside edge 25 of the top plate *f²* is stepped to different depths as at *n* (see Figure 6) and arranged so that if this top plate be placed in different angular positions the slots formed between the stepped parts *n* and the wall of 30 the drum *a* would come in line with the channels *g* thus varying the position of the channel entrances. As shown in Figures 7 and 8 the top plate *f³* is provided with a series of 35 holes *o* situated at different distances from the drum centre but arranged in an analogous way and with the same effect as the steps *n* of Figures 5 and 6.

In Figures 9, 10, 11 and 12 the top plate *f* is formed with slots *p* from the outside edge 40 in line with the channels *g* and extending radially inwards near to the outside diameter of the set of plates *e*. Between the top plate *f* and the set of plates *e* is inserted an interchangeable plate *q* of the same shape 45 as the underside of the top plate *f*. By having a series of such plates *q* with different outside diameters the positions of the entrances to the channels *g* can be varied merely by changing the plate *q*. In Figures

9 and 10 this plate *q* is of such a diameter, 50 that the channel entrances are situated close to the wall of the drum *a*. While in Figures 11 and 12 the plate *q'* is of a smaller diameter and consequently the channel entrances are situated at a greater distance 55 from said walls.

In Figures 13, 14, 15 and 16 the top plate *f* is arranged as in Figures 9 to 12 but, instead of a series of interchangeable plates *q* of different diameters, only one plate *r* is 60 fitted but this plate can be turned into different positions. In Figures 13 and 14 the outside edge of the plate *r* is stepped as at *s* so that according to the different angular positions of said plate, the effective length of 65 the slots *p* in the top plate *f* is varied, while in Figures 15 and 16 the plate *r'* is formed with a series of holes *t* at different distances from the centre but arranged in an analogous way to the steps *s* of Figures 13 and 70 14, thus producing the same effect on the position of the entrances to the channels *g*.

We claim:

1. A centrifugal drum, for the continuous separation of mixtures of a plurality of 75 fluids of different specific gravities containing solid particles in suspension, provided with a top plate adapted to keep apart the separated lighter and heavier fluid components during their discharge from the drum, 80 and adapted to determine the position of entrances to channels adapted to discharge the heavier fluid components at a relatively high velocity, so as to facilitate the discharge therewith of the separated solid particles 85 not deposited on the wall of the drum, and means adapted for varying the distance of said channel entrances from the centre of the drum thereby to vary the permissible deposit of solid particles on the wall of the 90 drum.

2. A centrifugal drum as claimed in claim 1, provided with a top plate, in which radial slots are cut from the periphery in line with the channels.

KARL JOHAN SVENSSON.
